UNITED STATES PATENT OFFICE.

WILLIAM H. MAYER, OF NEW YORK, N. Y.

DESIGN FOR FABRIC.

SPECIFICATION forming part of Design No. 29,915, dated December 27, 1898.

Application filed November 29, 1898. Serial No. 697,799. Term of patent 31 years.

To all whom it may concern:

Be it known that I, WILLIAM H. MAYER, a citizen of the United States, residing at the city of New York, borough of Manhattan, in the county and State of New York, have invented and produced a new and original Design for a Fabric, of which the following is a specification, reference being had to the accompanying drawing, forming a part thereof, in which is represented a plan view of a piece of fabric embodying the features of my design.

The design embodies fanciful floral figures, sundry of which have single and others dual foliage stems. The stems bear flowers, the leaves whereof are curled and radiate from a common center, while the centers of the flowers represent clusters of elliptically-shaped leaves arranged at an angle to the radial

leaves. Clusters of circular figures appear in pyramidal order adjacent to various of the flowers.

The leading feature of the design consists of a fanciful flower formed with leaves radiating from a common center and a center 25 representing a group of elliptically-shaped leaves at an angle to the radial leaves, a stem for the flower, and a cluster of circular figures adjacent to the flower and arranged in pyramidal order. 30

I claim—

The design for a fabric herein shown and described.

WILLIAM H. MAYER.
